C. W. SQUIRES.

CIRCUIT CLOSER.

APPLICATION FILED APR. 2, 1917.

1,341,347.

Patented May 25, 1920.

FIG. 1.

HIS ATTORNEYS

UNITED STATES PATENT OFFICE.

CHARLES W. SQUIRES, OF BEVERLY, MASSACHUSETTS.

CIRCUIT-CLOSER.

1,341,347.

Specification of Letters Patent.

Patented May 25, 1920.

Application filed April 2, 1917. Serial No. 159,092.

To all whom it may concern:

Be it known that I, CHARLES W. SQUIRES, of Beverly, in the county of Essex and State of Massachusetts, a citizen of the United States, have invented a new and useful Improvement in Circuit-Closers, of which the following is a specification.

My invention relates to a device which serves as a circuit closer and release and also 10 as a means to lock the circuit when closed.

My invention will be understood by means of the drawings in which it is shown diagrammatically.

Figure 1 is a diagram showing the essential parts of my invention connected to produce the desired results.

Fig. 2 is a section of two of the magnets showing their construction and the manner of supporting the end of the contact lever.

20 My invention is an improvement on a portion of the mechanism shown in my United States Patent No. 1,080,730, granted December 9, 1913, to which I refer for certain details of construction.

25 A is the trolley wire and B is the trolley. C is a contact rail, the construction of which is not shown in detail as it is fully described in the said patent. As in that patent, the trolley wheel moves over this rail and out

30 of contact for the moment with the trolley wire A. The only electric connection between the contact rail and the trolley wire A on which it is mounted and from which it is insulated, is through the electro-magnet 35 T (as in my said patent, see Fig. 14 thereof), and the wires t and t¹, one of which t is connected directly with the trolley wire A, while the other is connected to the contact rail C with which the trolley wheel B contacts.

40 The various mechanisms, except those mounted on the trolley wire A, are mounted on an insulating plate Y, preferably of slate, rectangular in shape but having a lateral projection y to receive the electro-magnet T and the parts associated with it.

When the circuit through the car is closed so that the car is drawing current from the trolley wire A, the coil T is energized. If the car circuit is not drawing current, the 50 coil T is not energized.

S is a switch member pivoted at s one arm of which rests normally on the core j of the magnet J. Its other arm normally rests on or in operative relation to the contact S¹

from which wire s¹ runs to one magnet of 55 the track switch (not shown), which is a switch of well known character.

This switch member S is connected by a link S⁴ with the armature lever T² pivoted at t². When coil T is energized the armature T² is lifted and, by means of the link S⁴, throws the switch member S from contact with S¹ to contact S², which is connected by wire s² with the other magnet in the track switch. As is well known, the energizing 60 of these two magnets determines the position of the switch tongue, the purpose of the electro-magnet J being to hold the switch member S in contact with either S¹ or S² while the car is going over the switch. 65 These parts and their operation are fully described in my said Letters Patent.

70 The objects to be attained by my present invention are as follows:—

To close the track switch circuit automatically as the car passes the contact rail, and lock it against operation by the following car until the first car has passed the switch, and then to effect automatically the release 75 of the parts so that they may return to their 80 normal position again as soon as the car has passed a given point represented in the drawings by the contact F.

Above the contact rail C is supported a lever a pivoted at a¹ and hanging down in 85 the path of the trolley wheel. The lever a is made of insulating material and carries a metal plate a² which is connected by the wire c with the main wire C¹. When the trolley wheel B passes over the contact rail 90 C it strikes the plate a² and a circuit is closed from the trolley wire A through t, T, t¹ to the contact rail C and thence through the trolley wheel to the plate a², wire c to wire C¹. The contact between the trolley 95 wheel B and the plate a² is momentary, existing only as the trolley wheel passes over a portion of the rail C and the lever falls back to its normal position, thus breaking the circuit again. It will be seen that this 100 circuit will only be closed when the trolley wheel moves in a direction to strike the plate a². The wire C¹ is connected with a sole-

noid D. G is a lever pivoted at g. This 105 lever is made of insulating material, but has upon it two contact plates, one d and the other d¹. The normal position of this lever G is that shown at 1, where it rests upon the

latch d^2 which forms part of the core of the solenoid D. This core and the core of the similar solenoid K comprise three members each, a plug d^3 (k^3) which closes one end of the opening through the solenoid D (K) and which is connected by wire d^4 (k^4) with the solenoid coil, next a spring member d^5 (k^5), which engages the rear end of the latch d^2 (k^2) and is electrically connected with both the plug and the core. The front end of the latch d^2 (k^2), which forms the front member of the core, is beveled off in such manner that upon the pushing up of the lever G it will slip by the latch d^2 (k^2) pushing it inward, and thereafter the latch will be forced forward by the spring so that it may serve as a rest for the lever G. When this solenoid is energized by current through the wire C^1 it will cause the retraction of the latch d^2 so that the lever G will drop by gravity. When the lever G is resting upon the core d^2 the circuit will be closed from it through the plate d on the lever G and thence to the ground H by wire h which is connected to the plate d. Upon the swinging of the lever a by the trolley wheel the circuit will be closed through C^1 , D, its latch d^2 , the plate d, wire h to ground H. The solenoid coil D being thus energized, withdraws the latch d^2 thus breaking the circuit and at the same time allowing the lever G to drop. When the circuit is broken the spring d^5 returns the latch into place. It will thus be seen that this circuit can never be closed unless lever G is resting on latch d^2 .

Below the lever G is a vertical solenoid E having a core E^2 supporting at its upper end a non-magnetic metal stud E^1 which, when the solenoid is not energized, projects slightly above its upper surface and engages the plate d^1 on the lever G when the lever G is in its second or lowest position. The solenoid E derives current from the trolley wire A by means of the wire C^2 which leads to a point e where it divides, one wire e^1 leading to the terminal c and the other e^2 leading to the coil E. The other end of the coil is connected by the wire e^3 to the core E^2 and stud E^1 .

The plate d^1 attached to the lever G is connected by the wire g^1 with one end of the coil J, the other end of which is connected, as above described, with one of the track switch magnets. When in its lowest position 2 the lever G rests on the end E^1 of the core E^2 . The circuit being then completed from the trolley wire A by wire C^2 through the solenoid E, its core E^2 and its stud E^1 , plate d^1 , wire g^1 to coil J, etc., the core E^2 is lifted because of the energizing of the solenoid E, and lifts the lever G into the position marked 3. To reach this position it snaps by the core d^2 of the solenoid D and also by the core k^2 of the solenoid K,

which is in all respects similar in construction to the solenoid D and is similarly lettered but with the letter k as indicated above, and rests on its latch k^2 . This causes the spring g^2 , which is mounted on the end of the lever G, to contact with the terminal c and close a circuit comprising the trolley wire A, wire C^2 , e^1 to c, the spring g^2 , wire g^3 , plate d^1 , wire g^1 to J and one of the arms of the switch S to the track switch. This short-circuits the solenoid E so that the core E^2 is released and drops, leaving the lever G resting on the latch k^2 . The coil J, however, is still energized, controlling the position of the track switch.

When the trolley B engages the releasing contact F a circuit is closed through wire C^3 , solenoid K, latch k^2 , plate d, wire h to the ground H. The solenoid K thus being energized, its latch k^2 is withdrawn and releasing the lever G, the lever drops into its normal position resting on the latch d^2 and thus breaking the circuit through J, so that all the parts resume their normal positions.

It is believed that from the above description the operation of my device will be understood. The first result will be the setting of the track switch connection one way or the other according as the magnet T is energized or not. The second result will be the energizing of the solenoid D by the entrance of the trolley into the section so that the lever G will be released and will drop from its normal position into position 2 and be immediately lifted to position 3 and be thereafter incapable of operation by a second car entering the switch section until the first car has left the section and the lever has been returned to its normal position.

During the operation of the device, the entry of another car into the switch area will not be effective to interfere with or change the circuit because the lever G will not be in position to be operated by the incoming trolley wheel.

A time limit device, such as is shown in my United States Patent No. 1,080,730, or in my application, Serial No. 47,579, may be used with this instrument if desired. In this case it may be placed in circuit with the solenoid E, the connection e^1 , c being omitted.

As other arrangements of circuits within the scope of my invention may be made to accomplish the same result, I do not mean to limit myself to the precise construction shown.

What I claim as my invention is:—

1. A normally-open electric circuit comprising a trolley wire and circuit-closing means comprising a trolley wheel and a pivoted contact member made of insulating material lying in the path of said trolley wheel and having means for electrical engagement therewith.

2. A normally-open electric circuit comprising a trolley wire and circuit-closing means comprising a trolley wheel and a pivoted contact member made of insulating material lying in the path of said trolley wheel and having means for electrical engagement therewith, said means being upon one side only of said contact member whereby the circuit will be closed only when the 10 trolley wheel approaches said member from a predetermined side.

3. A normally-open circuit comprising a trolley wire, a solenoid in said circuit and comprising a latch core adapted to be withdrawn 15 on the closing of said circuit, a switch member normally resting on said latch out of operative position and when so resting forming part of said normally-open circuit, means for closing said circuit whereby said 20 switch will be released, and means for moving said switch into operative position.

4. In an electric switch mechanism, a normally-open circuit, a solenoid therein, its core in circuit therewith, a switch member 25 normally resting on said core and in circuit therewith, means for closing said circuit whereby said core will be withdrawn and said switch member be released, and means to move it thereafter into operative position.

5. In an electric switch mechanism, a normally-open circuit, a solenoid therein, its core in circuit therewith, a switch member normally resting on said core and in circuit therewith, means for closing said circuit 35 whereby said core will be withdrawn and said switch member be released, and means to move it thereafter into operative position and hold it there.

6. In an electric switch mechanism, a normally-open circuit, a solenoid therein, its core in circuit therewith, a switch member 40 normally resting on said core, means for closing said circuit whereby said core will be withdrawn and said switch member be released, means to move it thereafter into operative position and hold it there, and means thereafter to release it whereby it may return to its normal position.

7. In an electric switch mechanism, a normally-open circuit, a solenoid therein, its core in circuit therewith, a switch member normally resting on said core and in circuit therewith, means for closing said circuit whereby said core will be withdrawn and 55 said switch member be released, and means to move it thereafter into operative position, means for holding it in operative position and means comprising a normally-open circuit adapted when closed to operate said holding mechanism whereby said switch member may be released to its normal position.

8. A normally-open impulse circuit, a normally-open track switch-operating circuit, and a normally-open release circuit,

trolley-operated means to momentarily close said normally-open impulse circuit, means to close said normally-open track switch circuit, trolley-operated means to close said normally-open release circuit, means operable automatically by the track switch circuit while energized to render ineffective the impulse circuit, and means operable by the release circuit when energized to effect the opening of the track switch circuit and 70 to return the parts to their normal operating position.

9. A normally-open impulse circuit, trolley-operated means to momentarily close said circuit, a track switch-operating circuit, a normally-open switch comprised therein, means operable when the impulse circuit is closed to effect the closing of said normally-open switch, automatic means operable to lock the track switch circuit in 80 closed position, a normally-open release circuit, trolley-operated means to close said circuit, and magnetic means comprised in said release circuit whereby the said switch member may be returned to its normal open 90 position.

10. The combination with a track switch-operating circuit, of a three-way switching member operable either to close said circuit, lock said circuit against operation by 95 its normal circuit-closing means, or to close a circuit whereby it will be released to be returned to its normal open position, trolley-operated means to cause said switch member to assume its closed position, automatic means comprising a solenoid and its core operable with the track switch circuit to cause said switch member to assume its locked position, and magnetic means comprising a magnet and its armature operable by trolley contact to release the said switch member from its locked position to assume its normal operating position.

11. The combination with a trolley-operated circuit-closing means, of circuit-opening means comprising a ground wire, a magnet coil, suitable connections and trolley-operated means adapted momentarily to energize said magnet coil.

12. A normally-open track switch circuit, 115 trolley-operated means to close said circuit, means operable automatically with the energizing of the track switch circuit to lock said track switch circuit against the circuit-closing means, and trolley-operated releasing means operable to effect the return of said locked circuit to its normal operating position.

13. A normally-open track switch-operating circuit, trolley-operated means to close 125 same, automatic means in said track switch circuit operable to disconnect the circuit-closing means, and a trolley-operated circuit-opening and unlocking means comprising a ground wire, a magnet coil, and suit- 130

- able circuit conductors effective when energized to open the track switch circuit and return the parts to their normal position.
14. In a track switch mechanism for trolley cars, a normally-open circuit adapted when closed to maintain the position of the track switch and a circuit-closing mechanism for said maintaining circuit comprising means normally in non-closing position, means operable by a second circuit controllable by the trolley whereby said maintaining circuit-closing means is released from its non-closing position, means adapted to move it from a non-closing to a closing position, and means adapted thereafter to release it whereby it will return to its normal position.

15. In a track switch mechanism for trolley cars having a trolley wire, a normally-open circuit comprising means to connect it with said trolley wire, means for closing it comprising a trolley wheel, a second circuit comprising a circuit closer therein, means in said first-named open circuit for holding said circuit closer normally out of circuit-closing position, said means being operable to release said circuit closer upon the electrical connection of said means with said trolley wire, and means for causing said circuit closer to close its circuit whereby when said last-named circuit is closed the position of the track switch will be controlled.

CHARLES W. SQUIRES.
